ARTICLE HANDLING DEVICE

Commodore D. Ryan, Los Angeles, Calif., assignor
to National Postal Meter Company, Inc., Rochester, N. Y., a corporation of Delaware

Application April 16, 1941, Serial No. 388,770

3 Claims. (Cl. 211—126)

This invention relates to devices for facilitating the handling of small objects en masse. It is particularly applicable to the handling of envelopes, and the like, before and after carrying out such operations as printing, sealing, etc.

A broad object of the invention is to simplify and facilitate the handling of envelopes, and the like.

Another object is to provide a device for supporting envelopes, and the like, en masse, so designed as to facilitate the compression of the envelopes in a row, whereby a plurality of the devices containing envelopes can be stacked one on top of the other without injury to the envelopes in the lower devices.

Briefly, the invention comprises a tray and a cooperating supporting rack on which the tray can be removably mounted. The tray has end walls interconnected by a bottom and one side wall, both of which are extensible to permit compression of a row of envelopes in the tray between the two end walls. Other features of the invention reside in a simple structure for locking the trays to the rack and for detachably mounting the rack on a machine in which the envelopes are to be treated.

The invention will now be fully explained by describing in detail a particular embodiment thereof, as illustrated in the drawings, it being understood that numerous departures from the exact construction shown can be made without departing from the invention.

In the drawings:

Fig. 1 is a front elevation of a rack and tray in accordance with the invention, the rack being shown mounted on a machine such as a mail-treating machine, and the tray being mounted in position on the rack;

Fig. 2 is a vertical section taken in the plane II—II of Fig. 1;

Fig. 3 is a detail vertical elevation, taken in the plane III—III of Fig. 1;

Fig. 4 is a detail section, taken in the plane IV—IV of Fig. 3;

Fig. 5 is a plan view of the tray, with a portion broken away;

Fig. 6 is a front elevation of the tray, with a portion broken away;

Fig. 7 is a side elevation of the tray loaded with envelopes compressed therein; and

Fig. 8 is a cross-section taken in the plane VIII—VIII of Fig. 6.

Referring to Fig. 1, a rack 1 in accordance with the invention is detachably supported upon the side of any suitable machine 2 and is adapted

to support two trays 3, only one of which is shown in Fig. 1.

The rack 1 comprises a vertical flat plate 4 which overlies the outturned flanges 5 on the ends of a pair of triangular plates 6, the flanges 5 being secured to the plate 4 in any suitable manner, as by spot welding. Each of the flanges 5 and the underlying portion of the plate 4 has a keyhole 7 near its upper end adapted to engage a supporting pin 8 extending from the machine 2. Each pin 8 has a head 9. There is also formed in each flange 5 and the underlying portion of the plate 4, at the lower end thereof, a notch 10 adapted to engage a headed pin 11 extending from the lower portion of the machine 2. It will be obvious that the rack 1 can be attached to the machine 2 by passing the heads 9 of the upper pins 8 through the large portions of the keyhole slots 7 and aligning the notches 10 with the lower pins 11 and then lowering the rack into the supported position, as shown in Figs. 1 and 2. The rack may be removed from the machine by reversing the procedure.

The triangular plates 6 are formed integrally with an upper plate 12, which extends between the plates 6 and interconnects them. This plate 12 constitutes a base to which are attached the lower ends of a pair of brackets 13—13, the latter being preferably of channel construction and comprising a web of irregular shape, as shown in Fig. 2, with inwardly extending flanges 14 thereon. Each bracket 13 is secured to the plate 12 by bolts 15 extending through the flange 14. The brackets 13 support a pair of shelf members 16 and 17, both of which are identical, the shelf member 17 being positioned above and rearwardly of the member 16. Both are secured to the brackets 13 by bolts 18 passing through the flanges 14 of the brackets.

Each of the shelves 16 and 17 is of very simple construction comprising a rectangular base plate 19 having a downwardly rolled upper edge 20 and leftmost edge 21, and having an upturned bottom flange 22 and an upturned end flange 23. Each end flange has a hole 24 and a notch 25 for locking the detachable trays 3 thereto in a manner to be described later.

Each of the trays 3 comprises a pair of telescoping sections 26 and 27, respectively, which are longitudinally slidable with respect to each other, within limits. Thus the section 27 comprises an end wall 28 which is formed by upturning the end of a bottom wall 29, and a side wall 30 (Fig. 8) which is formed by upturning one edge of the bottom wall 29. A handle plate 31 having a

curled upper edge is secured, as by spot welding, to the end wall 28. The adjacent edges of the end wall 28 and the side wall 30 are interconnected and the corner reinforced by an angle member 33 spot welded thereto.

The section 26, like section 27, comprises a bottom wall 29' and a side wall 30' formed integrally with an end wall 28', the latter having a handle 31' identical with the handle 31. However wall 30' is slightly narrower than the wall 30 (Fig. 8) and the top wall 29' is slightly narrower than the bottom wall 29, and these walls are slidably engaged at their free edges by inturned flanges 34 and 35, respectively, on the walls 30 and 29, respectively. The two sections 26 and 27 are therefore slidably supported for relative longitudinal movement. Inward movement of the two sections is limited by abutment of the inner edge 36 of the bottom wall 29' against the end wall 28, and separating movement of the two sections is limited by engagement of shoulders 37 and 38 on the walls 30' and 29', respectively, against the ends of filler strips 39 and 40, respectively, interposed between the wall 30 and its flange 34 and between the wall 29 and its flange 35, respectively.

Because of the angular positioning of the shelves 16 and 17 (Fig. 2), the trays 3 tend to remain in proper position on the shelves by their own weight. However, it is desirable to lock the trays in place on the shelves to preclude their accidental dislodgment as the result of careless handling. Hence the end wall 28 of each tray is provided with a tapered pin 42 which is adapted to be engaged in the hole 24 in the end wall 23 of the shelf, and with a headed pin 43 adapted to be engaged with the notch 25 in the end wall 23 of the shelf. A tray is locked in position by first inserting the pin 42 through the hole 24 until the angled reinforcement 33 (Fig. 4) lies against the end wall 23 of the shelf, while holding the upper portion of the tray away from the wall 19 of the shelf, and then rocking the tray rearwardly and downwardly about the pin 42 as a pivot to engage the pin 43 in the notch 25. When the tray has been locked in place on the shelf in the manner described, it will be found practically impossible to dislodge the tray from the shelf as the result of any normal operation on the contents of the tray. However, the tray can be instantly removed from the shelf by rocking the rear portion of the tray upwardly and forwardly to carry the pin 43 out of the notch 25 and then shifting the tray longitudinally to carry the pin 42 out of the hole 24.

The particular tray construction described is very convenient in handling compressible objects such as envelopes. Thus envelopes can be quickly loaded into the tray in handfuls while the tray is in extended condition. Then, after it has been loosely filled, the opposite end walls 28 and 28' can be pressed inwardly to cause the two sections 26 and 27 to slide together and compress the envelopes snugly together as shown in Fig. 7, in which the bodies of the envelopes are indicated at 44 and the upwardly extending flaps of the envelopes at 45. The friction between the cooperating sliding surfaces of the two sections 26 and 27 is sufficient to retain them in contracted position, in which the envelopes are tightly compressed, so that several loaded trays can be stacked one on top of the other without bending and damaging the envelopes in the lower trays.

As a specific example of the practical use of the tray and rack construction described, a mul-

ti-department concern may have a single mail stamping machine (the machine 2 in Fig. 1) to which mail is brought from all the different departments. Each department will be equipped with as many of the trays 3 as are necessary to contain its mail for the day. These trays may be supported in the department on a table while they are being loaded, during the day. As fast as the trays are filled, they are telescoped inwardly to compress the envelopes so that the trays may be stacked one on top of the other, without crumpling or damaging the envelopes in the lowermost trays. At the end of the day the filled trays may be carried in stacked condition to the mail room where the machine 2 is located, and the trays then placed one or two at a time on the rack 1, which is attached to the mail machine 2, while the envelopes are transferred by hand from the trays to the mailing machine. As fast as the trays are emptied, they can be removed from the rack 1 and restacked for convenience, and carried back to the department from which they came.

A particular advantage of the tray construction disclosed is that it is open not only at the top but on one side so that it readily handles envelopes of varying length, as well as envelopes of varying width. Furthermore, it is easier to place envelopes in and remove them from the open sided tray, particularly when supported at an angle as shown in Fig. 2, than with a conventional tray open only at the top.

Although for the purpose of explaining the invention a specific embodiment thereof has been described in substantial detail, it is to be understood that various changes may be made in the particular construction shown without departing from the invention, which is to be limited only to the extent set forth in the appended claims.

I claim:

1. In combination, a rack having a bottom wall, a side wall substantially perpendicular to said bottom wall and an end wall substantially perpendicular to both said bottom and side walls, means for supporting said pack with said end wall vertical and both said side and bottom walls inclined upwardly and outwardly from their line of intersection, an open top tray having a bottom wall adapted to rest against the bottom wall of said rack, a side wall perpendicular to said bottom wall and adapted to rest against the side wall of said rack, an end wall perpendicular to said bottom and side walls and adapted to rest against and be longitudinally located by the said end wall of said rack, one of said end walls having a headless pin and a headed pin extending therefrom and the other of said end walls having a hole positioned to receive said headless pin, and a notch in its upper edge positioned to receive said headed pin whereby said tray is detachably locked to said rack by moving said end walls together with the headless pin aligned with said hole and the headed pin out of alignment with said notch, and thereafter rotating the tray about the axis of the headless pin to carry the headed pin into engagement with said notch.

2. In combination, a rack having a bottom wall, a side wall substantially perpendicular to said bottom wall and an end wall substantially perpendicular to both said bottom and side walls, means for supporting said rack with said end wall vertical and both said side and bottom walls inclined upwardly and outwardly from their line of intersection, an open top tray having a bot-

tom wall adapted to rest against the bottom wall of said rack, a side wall perpendicular to said bottom wall and adapted to rest against the side wall of said rack, an end wall perpendicular to said bottom and side walls and adapted to rest against and be longitudinally located by the said end wall of said rack, a plurality of pins on one of said end walls, and means in the other of said end walls in registry with said pins when said tray is positioned on said rack for releasably securing said tray against movement in a plane parallel to the bottom of the rack and also against rocking movement about an axis coincident with one side edge of the rack bottom.

3. In combination, a rack having a bottom wall, a side wall substantially perpendicular to said bottom wall and an end wall substantially perpendicular to both said bottom and side walls, means for supporting said rack with said end

5 10 15 wall vertical and both said side and bottom walls inclined upwardly and outwardly from their line of intersection, an open top tray having a bottom wall adapted to rest against the bottom wall of said rack, a side wall perpendicular to said bottom wall and adapted to rest against the side wall of said rack, an end wall perpendicular to said bottom and side walls and adapted to rest against and be longitudinally located by the said end wall of said rack, pin means on one of said end walls, and pin receiving means in the other of said end walls in registry with said pin means when said tray is positioned on said rack for releasably securing said tray against movement in a plane parallel to the bottom of the rack and against rocking movement about an axis coincident with one side edge of the rack bottom.
